BERNARD F. STENZ, OF NEW YORK, N. Y., ASSIGNOR TO SIMPLEX SAMPLING ASSOCIATION, INC., OF NEW YORK, N. Y., A CORPORATION OF NEW YORK

DISPLAY DEVICE

Application filed September 7, 1929. Serial No. 390,974.

The present invention relates to a display device for showing a miniature representation of an object constructed of a patterned material, the pattern of the material being 5 proportionately reduced.

One object of the invention is to enable a purchaser of dress material of a given pattern to determine how a garment will look when made of that particular material and 10 to provide a miniature or reduced picture of a garment through which the material may be observed with the pattern of the fabric proportionately reduced with reference to the size of the miniature or reduced picture 15 of the garment, through which the material is visible. Further objects will appear in connection with the following specification.

As illustrated in the accompanying drawing, the invention is particularly adapted for 20 showing how a woman's dress or gown would appear when made up of a patterned dress material.

In the drawing Figure 1 shows in perspective the device in use.

25 Figure 2 shows a longitudinal sectional view of the device as shown in Figure 1, the displayed material being omitted.

Figure 3 is a sectional view of a modified form of the device.

30 Figure 4 is a front view of a modified form of stencil.

In its simplest form, as shown in Figures 1 and 2, the device comprises a reducing lens of glass 1, circular in form and fitted within 35 a circular metallic band 2, the band being supported by a post 3. The post 3 may have at its lower end the usual grip or handle (not shown) of an ordinary reading glass whereby the user may carry it and use it in the customary manner of using a reading glass. Preferably, however, the post 3 will be provided with a base 4 which may be mounted upon a table 5, the latter being provided with supporting legs 6 whereby it may be supported upon a table or counter 7. This will 40 position the device at a convenient height for the observer. Cooperating with the reducing lens 1 is a stencil 8 which may be produced by an opaque pigment or paint applied directly to one surface of the reducing

lens 1 leaving at its center a clear space 9 having the outline of a dress or garment. The paint applied to the lens will, of course, be of such color and consistency as to render the lens opaque or non-transparent at all 55 portions excepting that portion showing the picture.

As shown in Figure 1 when a piece of patterned fabric 10 is viewed through the clear portion which shows a picture of a gown in 60 reduced size, assuming that the fabric has been properly focused with relation to the position of the reducing lens, the observer will see a picture of the gown in reduced size with the pattern of the fabric proportionately reduced with relation to the reduced picture of the gown.

For convenience in displaying textile fabrics in the bolt a standard 11 having at its upper end a supporting bar 12 with upturned 70 guards 13 may be provided, the standard 11 passing through a slot 14 in the base or table 5, which permits the standard 11 to be adjusted toward and from the reducing lens, to secure a proper focusing of the material with 75 relation thereto, and the standard 11 carries at its lower end a suitable locking device, as for instance a winged nut 15 engaging the threaded end of the standard, by means of which it may be secured in adjusted position. 80 The table 5 may be of such a length that the bolt of fabric 10 may rest thereon when the fabric is draped over the bar 12.

In the modification of the device shown in Figures 3 and 4, the stencil instead of being 85 produced by paint applied to one surface of the lens, may be formed separately comprising a transparent sheet of material 16, such as glass or celluloid, which may be painted as shown at 17 leaving a clear portion 18 of the gown, or it may consist as shown in Figure 3 of a sheet of paper or other thin opaque material 19 cut out as indicated at 20 which may be secured by an adhesive to the transparent sheet of material 16. As indicated in Figure 4 this stencil may be square instead of round, assuming that the reducing lens may be square or supported in a square frame. Suitable means, such as a detachable frame or clips 21, will be provided whereby the re- 95 100

movable stencil may be connected to and supported in close relation to one face of the reducing lens.

By forming the stencils separately and providing means whereby they can be quickly adjusted in proper relation to the reducing lens, it is obvious that a plurality of stencils showing reduced representations of various objects and garments may be provided, such pictures being changed to show various styles as the styles of garments change.

I am aware that it has heretofore been proposed to display textile fabrics in a manner to afford an observer a representation of a garment made therefrom and that for this purpose stencils have been employed either cut out of opaque material or made of celluloid or other transparent material and that such stencils have been either of reduced 10 miniature size or of full size and laid over in close contact with the material to be displayed. When such stencils are made of full size they are much too bulky and cumbersome for general use, particularly to display to a purchaser in a store at the counter where such materials are sold, and they are generally employed more as window displays and have been more or less successful for that purpose. Where stencils have been made to 20 show the garment or object in miniature form when laid upon the fabric the pattern of the fabric when viewed through a reduced picture of the garment cannot, of course, give the observer an accurate picture of the appearance of the gown made of such fabric, because of the relatively large size of the pattern of the fabric as compared with the picture of the gown.

In operation the display device is supported at a suitable distance from the patterned fabric and from the eye of the observer, so that the proper focusing of the fabric with relation to the picture of the article shown on the display device will result in reducing the pattern with relation to the size of the object shown on the display device. The observer looking at the display device sees a picture of the object in reduced size with the pattern of the fabric correspondingly reduced and gets a visual impression of how a particular patterned fabric will look when made up.

The term "stencil" as used in the foregoing specification is intended to include not only the usual "cut out" form in which the picture is formed by cutting out a sheet of opaque material, but also as indicated the forming of such stencil by paint applied to the reducing lens or to a transparent sheet separate from the lens or any and all forms of opaque bodies showing a cut out or transparent picture of the object to be displayed. The principal feature of the present invention consists in the combination of such a stencil with 60 a reducing lens whereby the patterned ma-

terial when seen through the stencil will have its pattern as thus viewed, correspondingly reduced in size relatively to that of the object shown on the stencil.

I claim:

1. A display device comprising a reducing lens and an opaque stencil defining in reduced size a picture of an object, the reducing lens and stencil being in close relation to each other whereby a patterned material may be viewed through the picture and lens, with the pattern of the material reduced with relation to the size of the picture.

2. A display device comprising a reducing lens and an opaque stencil formed by a coating directly applied to one face of the reducing lens and defining in reduced size a picture of an object, the lens being exposed through the picture of the object.

3. A display device comprising a reducing lens and an opaque stencil defining in reduced size a picture of an object through which and the reducing lens a patterned material may be visible, means for supporting the reducing lens and stencil, a support for the material to be viewed therethrough, and means for adjusting the material support and lens relatively to each other to secure a proper focus.
